UNITED STATES PATENT OFFICE.

FRANK J. FREY, OF QUINCY, ILLINOIS, ASSIGNOR TO THE H. WETTER MANUFACTURING COMPANY, OF MEMPHIS, TENNESSEE.

DESIGN FOR A STOVE.

No. 37,608.

Specification for Design.

Patented Oct. 31, 1905.

Application filed August 29, 1905. Serial No. 276,309. Term of patent 7 years.

To all whom it may concern:

Be it known that I, FRANK J. FREY, a citizen of the United States, residing at Quincy, in the county of Adams, State of Illinois, have invented a certain new, original, and ornamental Design for Stoves, of which the following is a specification, reference being had therein to the accompanying drawing, forming part

thereof, which shows a perspective of my design for stoves.

I claim—

The ornamental design for a stove, as shown.
FRANK J. FREY.
